UNITED STATES PATENT OFFICE.

MINOR M. DAVIS AND AUGUSTUS J. EAVES, OF NEW YORK, N. Y.

MULTIPLEX-TELEGRAPH SYSTEM.

1,045,953.

Specification of Letters Patent.

Patented Dec. 3, 1912.

Application filed February 7, 1912. Serial No. 675,986.

To all whom it may concern:

Be it known that we, MINOR M. DAVIS, a citizen of the United States, and a resident of the borough of Brooklyn, county of Kings, city and State of New York, and AUGUSTUS J. EAVES, a citizen of the United States, and resident of the borough of Manhattan, city, county, and State of New York, have invented certain new and useful Improvements in Multiplex-Telegraph Systems, of which the following is a specification.

One of the main objects of this invention is to provide means whereby the outgoing signal currents may be directed around or past the receiving instruments, that is to say the neutral relay or polar relay, and delivered to the line, a corresponding balancing circuit being carried to the artificial line. Another object of the invention is to provide means for conducting around the receiving instruments the inductive disturbances coming in over the line when such disturbances are of such a character and of such strength as to be likely to disturb the receiving instruments.

Another object of the invention is to provide means between the pole changer and the current generators to prevent sparking between the contact points and the armature of the pole changer. This spark preventing apparatus when used in the same apparatus with means for delivering the outgoing signal impulses to the line around or past the receiving instruments, operates with great efficiency.

The invention has other important objects and advantages, which will appear herein-after and will be readily appreciated by one skilled in the art.

In the drawings, Figure 1 is a diagrammatic view of a quadruplex telegraph apparatus showing only one end thereof; and Fig. 2 a similar view showing a slight variation in the arrangement of the means for conducting the outgoing signal impulses around the receiving apparatus.

Referring to the various parts by numerals, 1 and 2 designate the current generators, 50 the positive side of 1 and the negative side of 2 being connected to the stops 3 and 4 of the pole changer 5. The pole changer is operated through the key 6 in the usual manner to put positive or negative current on the line, the armature of said pole changer being connected to the line in the usual way. 55 The transmitter 7, is arranged in the usual

manner to increase or decrease the current on the line, said transmitter being operated by the key 8. The armatures of the pole changer and of the transmitter are connected by a conductor and in said conductor is inserted a resistance 10. The back stop 11 of the transmitter is connected to ground through a resistance 12. The current from the armature of the transmitter is split at 13, in the usual manner in quadruplex apparatus, and is carried through the neutral relay 14 and the polar relay 15, one side going to the main line 16 and the other portion going to the artificial line 17. The artificial line may be made up in any desired manner and provided with means whereby it may be balanced with the main line. In the arms of the bridge connecting the main conducting wire with the ends of the bridge wire are arranged resistances 18, and in the bridge wire 19 is interposed a condenser 20.

In the form of the apparatus shown in Fig. 1 conductors 21 and 22 are connected to the main conductor at a point between the armature of the transmitter and the point where the current is divided or split. As shown in this view these wires are connected at the point where the current is divided, 80 that is to say at the inner or home ends of the arms 18 of the bridge. These conductors are connected at their other ends, one to the main line and the other to the artificial line, thereby making a path for the current 85 around or past the receiving instruments. In each of these conductors is interposed a condenser 23, and between said condenser and the main conductor is placed a resistance 24. By this arrangement a sharp impulse of current or "kick" will pass immediately to the main line through the resistance and condenser in conductor 21, thereby 90 quickly and sharply raising the potential of the line to the peak of the signal wave. The 95 result of this is that the signal impulses reach their maximum strength on the main line almost instantly. Where the current impulse is entirely sent through the receiving instruments the peak of the wave is 100 reached slowly, whereas with the apparatus shown herein the wave would show a sharp rise to its peak and then a gradual return to zero. It is, of course, manifest that a balancing impulse of current will be transmitted through conductor 22 and its resistance and condenser to the artificial line. The 105 conductors 21 and 22 also serve to take up the inductive disturbances on the main line.

and to prevent them materially affecting the receiving instruments, these disturbances being usually caused by alternating currents picked up by the main line. The conductors 5 21 and 22 with their condensers and resistances also permit of the quick discharge of the coils of the receiving instruments upon the reversals of the current so that said coils do not discharge to ground back 10 through the transmitting instruments. It is manifest that by this arrangement sparking at the contact points of the pole changer, is practically eliminated.

Around the resistance 10 in the main conductor is arranged a conductor 10^a and in said conductor is arranged a condenser 10^b. The object of this arrangement is to provide a path for the inductive disturbances picked up by the main line to pass around 15 the resistance 10 to earth. These disturbances are caused by alternating currents and these currents will readily pass through the condenser 10^b and thence to earth through the pole changer. The conductors leading 20 from the generators 1 and 2 to the stops or contacts of the pole changer are connected together by a wire 25 and in this wire are interposed two condensers 26 and 27, the wire or conductor between said condensers 25 being grounded at 28. This arrangement 30 prevents sparking at the contacts of the pole changer and operates with great efficiency when used in the same apparatus with a means for conducting the outgoing currents 35 around and past the receiving instruments. The wire 25 and the condensers 26 and 27 being grounded at 28, as described, provides a direct path to earth for the alternating currents picked up by the main line.

40 In the apparatus illustrated by Fig. 2 of the drawings conductors 22^a and 23^a are connected to the ends of the bridge wire. In this arrangement of the apparatus the resistance 24 is omitted, the resistances in 45 the arms of the bridge taking place of and serving the same function as the omitted resistances. This arrangement of the apparatus gives practically the same results as the arrangement shown in Fig. 1. In some 50 arrangements of apparatus we prefer the construction shown in Fig. 1, as it is sometimes desirable that the resistances in the arms of the bridge shall be different from the resistances in the by-pass conductors 21 55 and 22 to get the best results.

What we claim is:

1. A quadruplex telegraph apparatus comprising main and artificial lines, transmitting instruments including means for reversing the polarity of the line and means for increasing and decreasing the current on the line, receiving instruments, conductors to carry outgoing currents around the re-

ceiving instruments to both the main and artificial lines, a condenser arranged in each of said conductors and a resistance arranged in each of said conductors between said condensers and the transmitting instruments, in combination with two generators arranged with the positive pole of one and the negative pole of the other connected to the means for reversing the polarity of the line current, a resistance in each of said connections, a conductor connecting said generators together at a point between the resistances and the pole changer, two condensers arranged in said conductor, the conductor between said condensers being connected to ground. 65 70 75

2. A multiplex telegraph apparatus comprising a main line, two generators, a pole changer, a conductor connecting the positive pole of one generator to the pole changer, a conductor connecting the negative pole of the other generator to the pole changer, a 80 resistance in each of said conductors, a conductor connecting the generators together between the resistances and the pole changer, two condensers arranged in said conductor, said conductor between the condensers being connected to a ground. 85

3. A multiplex telegraph apparatus comprising a main line, two generators, a pole changer, a conductor connecting the positive pole of one generator to the pole 95 changer, a conductor connecting the negative pole of the other generator to the pole changer, a resistance in each of said conductors, a conductor connecting the two generators together between the resistances and 100 the pole changer, two condensers arranged in said conductor, a ground for said conductor between the condensers, a transmitter connected to the main line, a resistance in said line between the transmitter and the pole changer, a conductor connected to said main line around the said resistance, a condenser in said conductor, receiving instruments connected to the main line and the artificial line, conductors connected to the 110 main line and to the artificial line, both of said conductors being connected to the main line between the transmitter and the receiving instruments, a condenser in each of said latter conductors and a resistance in each 115 of said conductors between said condenser and the transmitting instruments.

In testimony whereof we hereunto affix our signatures in the presence of two witnesses this sixth day of February 1912.

MINOR M. DAVIS.
AUGUSTUS J. EAVES.
